APPARATUS FOR INSTALLING CONTINUOUS ROWS OF FLUORESCENT LIGHTING FIXTURES

Donald H. Nietz, 30 7th Ave. NE., Rochester, Minn.

Filed Jan. 8, 1964, Ser. No. 336,491

7 Claims. (Cl. 254—4)

The present invention relates generally to light fixture installing devices and more specifically to an apparatus for assembling, elevating and installing continuous rows of fluorescent lighting fixtures.

In recent years it has been a common practice in commercial lighting installations e.g. in school classrooms etc. to form continuous rows of lighting fixtures from individual commercial units. The smaller fixtures are secured together to form continuous rows of lights, the lengths of which are often in excess of twenty feet. While such rows are not unusually heavy they are somewhat bulky to handle and usually require a number of workers to assemble and raise the assembled units to a position of installation.

Due to the nature of the fixtures which are usually formed of lightweight sheet metal the fixtures are frequently twisted or bent out of shape at the ends where bolted together, if the rows are assembled on the floor, and raised by hand to their point of installation. Thus special attention is required to prevent warping and deformation of the units. Otherwise, at least two workmen are required to raise the individual units and fasten them to the ceiling.

Another problem has been the lack of an adequate working surface on which such units can be assembled with a minimum amount of handling. For example the fixtures are frequently installed in semi-finished buildings or structures thus providing a somewhat inadequate assembly area in which to work.

Thus in view of the above problems encountered in the art it is one object of the invention to provide a light fixture installing apparatus wherein individual fixtures can be laid out and assembled into prescribed rows on a convenient working surface and elevated with the surface to their position of installation.

Another object of the invention is to provide an apparatus for installing electrical lighting fixtures which is easily portable, due to folding of component parts.

Yet another object of the invention is to provide an apparatus for installing continuous rows of electrical lighting fixtures which is easily manipulated by a single worker and can be set up, taken down and moved to a new location in a minimum amount of time and with a minimum amount of effort.

Still another object of the invention is to provide an apparatus for installing rows of fluorescent lighting fixtures in which twisting and warping of the units is substantially obviated.

Other objects and advantages will become apparent in the following specification and appended drawings in which:

FIG. 1 is a front elevational view of the preferred embodiment of the invention;

FIG. 2 is a side elevational view of a portion of the device of FIGURE 1;

FIG. 3 is a plan view of a portion of the device of FIGURE 1;

FIG. 4 is an isometric view of the moveable carriage employed in the device of FIGURE 1;

FIG. 5 is a diagrammatic view of the method of attaching the support wings of the device of FIGURE 1 to the moveable carriage;

FIG. 6 is an isometric view of one section of the support wing employed in the device of FIGURE 1;

2

FIG. 7 is a schematic sectional view of the leveling device employed with the support wing of FIGURES 2 and 6;

FIG. 8 is an isometric view of one embodiment of an end member suitable for employment on the support wings of the device of FIGURE 2;

FIG. 9 is an isometric view of another embodiment of an end member similar to the device of FIGURE 8;

FIG. 10 is a sectional view taken generally along line 10—10 of FIGURE 1 of the device for attaching the winch employed in the device of FIGURE 1;

FIG. 11 is a sectional view of the device of FIGURE 10 taken generally along line 11—11 of that figure;

FIG. 12 is a sectional view taken generally along line 12—12 of FIGURE 10; and

FIG. 13 is a side elevational view of the center member employed in the device of FIGURE 10.

Generally speaking the present apparatus allows light fixtures to be laid out on suitable extension arms or wings, assembled, and elevated to the ceiling where they can be bolted or fastened to the same.

Previously it has required a minimum of two workers to hold an 8' fixture in position and fasten at ceiling after carrying up a step ladder to the ceiling which is normally about 8'6" to 9' high. Longer rows require at least one more workman per fixture. To be specific, a thirty-two foot row consisting of four eight foot units requires four men and extreme care to lift the row up step ladders to the ceiling.

Lighting fixtures such as employed in the instant invention come in standard trade lengths which are four and eight feet. The fixtures are fastened to the ceiling by screws after they are bolted together and elevated into position to form a completed length or row, or are individually fastened to the ceiling and bolted together.

Referring now to the preferred embodiment of the invention as illustrated in the drawings. The installing apparatus 10 as seen in FIGURE 1 includes a portable elevator platform 12 on which is mounted a movable carriage 14. A pair of light fixture extension arms or wings 16 is pivotally mounted on the carriage 14 as herein-after described and project laterally of the platform 10 when in a fixture supporting position.

The elevator platform 10 includes a substantially rectangular base 17 formed of front and side angle members 17a and 17b which are welded or otherwise secured together in a fixed relationship. Rollers or casters 18 are provided on the base 17 and facilitate ease of manipulation of the elevator platform 10 during the process of installing light fixtures.

Also provided on the front of the base 17 is an upright substantially H shaped frame 20 which is composed of vertically extending U shaped side angles and transverse or laterally extending bracing members or angles 20b positioned therebetween. A pair of rearwardly and downwardly projecting angles 20c are provided between each side angle and the top of the base 17 to add rigidity and strength to the platform 10.

As shown in FIGURES 1, 3 and 4, the previously mentioned carriage 14 is designed for vertical movement with respect to the H shaped frame member 20 and is provided with a pair of guide rods 22 the ends of which project into slots 20a' in angles 20c when the carriage 14 is positioned on the frame 20.

Movement of the carriage 14 and wings 16 is afforded by the provisions of a commercial boat trailer hoist or winch such as Model No. 29 as manufactured by Fulton Co., of Milwaukee, Wisconsin and indicated generally by the numeral 24. A support rope or cable 26 is attached at its one end to the pulley of the winch 24 and at its opposite end to an eye bolt 28 on the carriage 14. Thus as the winch is operated by the crank 24a the cable 24

which also extends over an idler pulley 30 on frame 20 causes the carriage 14 to be lifted and also guided during its movement by the rods 22.

Referring now to support wings 16 which are designed in such a way as to be easily assembled or collapsed as the need requires. Each support wing 16 includes a plurality of wing sections 16a which are releaseably secured together to complete their respective wing 16 when the wing is in a support position. Similarly each section can be collapsed in such a way that the wing is folded accordian style alongside the elevator platform 12 and rests on the base 17 when transported. The latter position provides an apparatus which is compact, easily portable, and whose size permits its movement through standard size doorways.

The somewhat rectangular wing sections 16a are constructed of thinwall light weight tubular material including longitudinal strut members 16b, transverse connecting members 16c and diagonal bracing members 16d. Cross bracing members 16d' are also provided (see FIGURE 6) to give added rigidity to the wing.

Each wing section 16a is releaseably joined to a mating section 16a by hinges 32 and screw type leveling adjustments 34.

The wings 16 are attached to the carriage 14 by means of a support shaft 36 (see FIGURE 5) which projects through aligned openings in mating lugs 14e and 16e on the carriage 14 and the wings 16 respectively.

Each wing 16 is retained in a fixture support position by angle hook type leveling retainers indicated by the numeral 40. When the wings 16 are moved to a support position the angle hooks 40 which are pivotal on a shaft 37, project over the side angle bars 14b of the carriage 14 and have threaded ends on their shank 40b which allow each wing to be leveled with respect to the top surfaces of the carriage and the opposite wing. Thus the transverse members 16c on each wing are in alignment and provide a bench or working surface on which a row of light fixtures such as 42 (FIGURE 1) can be assembled. A suitable continuous but light weight plate or work surface can be secured to the top of wings 16 but in most practices may not be required.

The carriage 14 projects somewhat rearwardly of the H shaped frame 20 as seen in FIGURES 3 and 4 and is formed of a plurality of angle members 14a, 14b and 14c. The angles 14a extend upwardly and are joined by transverse horizontal members 14b and 14c which form a rectangular support surface 15.

Similar side angle bars 14b and 14c are spaced apart below the suport surface 15 and it is on angle bars 14b that lugs 14e are fastened to support the shafts 36 of wings 16, the later being shown more specifically in FIGURE 5.

The winch 24 for raising and lowering the carriage 14 is suitably attached to the frame 20 as shown in FIGURES 10, 11, 12 and 13. The winch 24 is attached to bars 24c by bolts 24c' on a rotatable shaft 24b. The shaft in turn being journaled for rotation in slots 24d in an outer fixed sleeve 24a welded between members 20b on the frame 20. The slots 24d extend radially around the sleeve 24a and are provided with aligned upwardly projecting portions which receive the bars 24c when the winch 24 is swung to an outward or operative position. As the winch is operated to raise the carriage 14 the tension on the cable 26 causes the rotatable shaft 24b to be lifted and the bars 24c engage the projecting portions which prevent lateral displacement of the shaft 24b and winch 24. When the carriage 14 has been lowered however the bars 24c drop free of the projecting portions of the slots and the winch 24 can be swung inward to an inoperative position as indicated by the arrow 25 of FIGURE 10.

In certain instances it may be desirable for additional length purposes to provide lighter end sections for the

wings 16. The latter can be accomplished by the devices shown in FIGURES 8 and 9. A single U shaped bar 44 can be employed with sleeve type connectors 46 having thumb screws 48 to fasten the connector to the end of an adjoining wing section and to the end member 44.

Similarly, the end member 48 of FIGURE 9 has upwardly and outwardly projecting struts 48a and connectors 46 with screws 48 for attachment to an adjoining wing section.

Referring now to the operation of the apparatus 10, the wings 16 are moved to a support position from a collapsed position in which the sections 16a are alongside the frame 20, the wings having been previously released by the leveling retainers 34 and angle hooks 40.

15 The winch 24 is swung into position and operated by the handle 24a to move the carriage and wings to a desirable working level above the floor 50. At this time the winch lock lever 51 is put into a lock position and a workman then proceeds to assemble the individual light units 41 into a row 42. When the latter is accomplished the winch lock 51 is released, the handle 24a is operated to elevate the carriage 14, arms 16, and row 42 into its recess 54 in the ceiling 52. The workman then places the winch lever 51 in a lock position and proceeds to attach the row 42 to the ceiling. When the attachment to the ceiling is completed the above process is repeated i.e. the carriage is lowered and the wings are either collapsed for movement to an adjoining room or remain in a support position to receive a new row of lights.

Thus in the above description I have presented a detailed description of my invention together with certain ways by which it can be carried out. It is not intended to limit the invention to the particular form shown but to include all such modifications as will occur to those skilled in the art as evidenced by the scope of the appended claims.

Now therefore I claim:

1. In a light fixture installing apparatus the combination including, a portable elevator platform, a fixture support wing hinged to and moveably mounted on said platform and means cooperating with said platform and said wing for causing movement of said wing between a first position in which a fixture is received on said wing and a second position in which said wing and said fixture are moved to a fixture installing position, and means for retaining said wing in said positions.

40 2. In a light fixture installing apparatus the combination including, a portable elevator platform, a first and a second support wing moveably mounted on said platform and hinged to said platform, said wings movable between a first fixture receiving position and a second fixture installing position, a retainer means movably mounted on said wings and cooperating with said wings to engage said platform and retain said wings in said positions, and means cooperating with said wings and said platform for causing said movement.

3. In a light fixture installing apparatus the combination including a portable elevator platform, said platform having an upright frame thereon, a first and a second light fixture support wing on said platform and each provided with a work surface movable between a collapsed position substantially parallel to said frame, a support position and a light fixture installing position normal to said frame, a winch means on said platform for moving said wings between said support and said installing positions and means provided whereby said winch can be rotated about an axis on said frame between an operative and an inoperative position.

4. The device of claim 3 wherein said platform includes a substantially vertical frame and wherein said wings when in said collapsed position are supported on said retaining means by said hinge on said frame substantially parallel thereto.

5. The device of claim 3 in which a hinge means is provided intermediate said wings and said platform and wherein a retainer means is provided for cooperation with said platform and said wings to retain said wings in a fixture support position.

6. The device of claim 3 wherein said winch is locked in at least one of said positions by the weight supported by said winch.

7. In a light fixture installing apparatus the combination including a portable elevator platform provided with a vertically movable carriage thereon, at least one fixture support wing pivotal on said carriage between a first substantially vertical position alongside said carriage and said platform and a second position in which said wing is substantially normal to said carriage and said platform, a retainer means cooperating with said wing and said carriage to retain said wing in said second position, and means for causing movement of said carriage and said wing between said second position at which a

fixture is received on said wing and a third fixture installing position.
